SELF-CLEANING HUMIDIFIER

James F. King, Jr., Winston-Salem, N. C., assignor to The Bahnson Company, Winston-Salem, N. C., a corporation of North Carolina

Application February 18, 1952, Serial No. 272,038

14 Claims. (Cl. 299—63)

This invention relates to humidifiers and particularly to humidifiers of the type wherein water is supplied to a rapidly rotating impeller disk from which it is thrown by centrifugal force against a grid ring having a row of stationary blades or teeth circumferentially surrounding the path of the periphery of the disk and thus atomized to be entrained by a stream of air blown past the humidifier.

In known humidifiers of this type, which generally comprise a motor, a motor shaft, a disk mounted on the shaft, a water supply to the surface of the disk near its axis, a grid ring having an annular row of teeth surrounding the disk and an imperforate bowl-like casing peripherally surrounding the blades or teeth, certain difficulties have been encountered in the operation of the devices due to the collection of lint, dirt, etc., on the grid ring. In the case of a humidifier operated in a room wherein there is an appreciable amount of lint in the air, such as in a textile mill, the lint is drawn into the air stream and is deposited on the rim of the casing and on the grid ring where it collects moisture and, due to the passage of the air, extends in the direction of the air stream in elongated tassels or "whiskers." Moisture which is deposited on these tassels by the passage of the moisture-laden air and/or by drainage from the casing, is blown from the collected lint in the form of drops which injure the materials being manufactured. Similar undesirable effects result from the formation of drops on the lint which is caught by and collected on the grid ring.

U. S. Patent No. 1,966,872, issued July 17, 1937, discloses a humidifier structure wherein the formation of stringy, tassel like deposits of large amounts of lint or other foreign matter on the rim of the casing is rendered impossible. Humidifiers of the general type with which the invention is concerned are disclosed also in U. S. Patents Nos. 1,544,418 and 1,745,239 to Bahnson.

It is an object of the present invention to provide a humidifier structure which is adapted to prevent the accumulation of lint and dirt and the formation of tassels or whiskers on the grid ring, e. g. the teeth thereof.

It is a further object to provide means for effecting periodic rotation of the grid ring so as to move the teeth of the ring past a stationary cleaning device for the teeth, the device for rotating the ring being constituted by a small turbine powered by the water under pressure which is otherwise normally delivered to the impeller disk for atomizing during the humidifying periods, and the cleaning device preferably being constituted by one or more small spray nozzles positioned adjacent the grid teeth which are also supplied by the pressure water.

A more specific object is to provide an automatic cleaning device for the teeth of the grid ring comprising a small water turbine for rotating the grid teeth past a stationary cleaning unit, a humidity controlled inlet pipe for bringing in water under pressure to the humidifier, a valve having an inlet port connected to the inlet pipe and two outlet ports connected respectively to an outlet pipe leading to the ring driving turbine and a second outlet pipe

5 leading to the impeller disk, and means controlled by the ring as it rotates for controlling the valve in such manner that water is delivered to the turbine for a predetermined period at the beginning of each humidifying period.

The foregoing as well as other objects and advantages of the invention will become more apparent from the accompanying drawings which illustrate a preferred embodiment thereof when taken in conjunction with the accompanying description.

10 In these drawings:

Fig. 1 is a front elevation with the cover plate for the impeller disk removed;

Fig. 2 is a vertical section taken on line 2—2 of Fig. 1;

Fig. 3 is an enlarged detailed view of the valve and its control as seen from the front in Fig. 1;

Fig. 4 is a similar view of the valve and control as seen from the rear;

Fig. 5 is a bottom plan view of the valve and its control;

Fig. 6 is a view of the valve in section;

Fig. 7 is another view of the valve with part of the cover plate broken away;

Fig. 8 is a view in top plan of the cam by which the valve is controlled;

Fig. 9 is a view in side elevation of the control cam for the valve; and

Fig. 10 is a view partly in section of the spray nozzles.

With reference now to the drawings, 10 is a casing for deflection of an air stream passing to the humidifier unit, the air stream direction being from right to left with respect to the apparatus illustrated in Fig. 2. A main shaft 11, receiving power from any suitable source such as a motor 12, drives a rotary water impeller disk 13 fixed to the shaft. Water is supplied to the unit through an inlet feed pipe 15, in which is placed a main valve 20 that is under the control of a humidity responsive device 21, as legended on the drawing, such as any of the well known types of humidistats commonly available.

40 A grid ring 18 is provided with an annular row of teeth 19 against which water is thrown from the periphery of the continually rotating disc 13 thus breaking up the water into a fine mist which becomes entrained in the air stream passing by the casing 10. Ring 18 is mounted for rotation, it being attached to the outer rotatable race 56 of a ball bearing assembly, the inner stationary race 57 being secured to casing 10 and the ball bearings being shown at 58. However as will be explained hereinafter, grid ring 18 is normally stationary except for a brief period at the beginning of each humidifying operation when it is caused to rotate and to thus move the teeth 19 past a stationary nozzle 59 through which water is discharged thus cleaning off the teeth.

55 When the humidifier unit is in operation motor 12 driving the impeller disk 13 may be run continuously, but in accordance with normal procedures, water will be supplied to the impeller disk 13 through line 55 only when the relative humidity of the air being conditioned falls below the desired value, causing valve 20 in pipe 15 to open. This valve recloses when the air under treatment has regained its desired moisture content.

60 Inlet pipe 15 extends from valve 20 to a second valve 60 which as seen clearly in Fig. 6 includes an upper valve chamber 61, a lower valve chamber 62, a wall 63 separating the two chambers and a valve stem 64 which passes through and operates in a central aperture 65 in the wall 63. Valve stem 64 carries an upper washer 66 which seats upon and controls fluid flow from the upper end of aperture 65 leading to chamber 61 and a lower washer 67 which similarly seats upon the lower end of aperture 65 and controls fluid flow to chamber 62.

65 For guiding valve stem 64 in its movement within aperture 65, diaphragms 68, 69 are employed in the upper and lower valve chambers. These diaphragms have

their rim portions anchored in the cylindrical walls of the valve chambers and are secured to the valve stem 64 at their centers by machine screws 70 which pass through the diaphragms and washers into the opposite end faces of the stem.

Disposed between the upper end wall of the valve casing and the upper diaphragm 68 is a coiled spring 71 which bears against this diaphragm to thereby normally load the valve stem in the downward direction to the position shown in Fig. 6. In this position, water entering valve 60 through pipe 15 will accordingly pass through an internal passageway 72 in partition wall 62 to central aperture 65, thence downward into lower valve chamber 62, out of chamber 62 via another internal passageway 74 leading through wall 63, and outward from valve 60 through pipe 75 which leads to a small turbine 76. Water issuing from nozzle 77 under pressure impinges upon the blades 78 of the turbine rotor 79 causing the latter to rotate. Water discharges from the turbine rotor through an outlet 79a and drops upon the continuously-rotating disk 13 which breaks it up into a fine mist that becomes entrained in the passing air stream.

Turbine rotor 79 serves to rotate the grid ring 18 and the coupling between the two is constituted by a reduction gear train, shown best in Fig. 1, and which includes pinion gear 80 driven by rotor 79 meshed with ring gear 81 which drives pinion 82 that meshes with ring gear 83 that drives pinion 84 that meshes with the teeth 56a on bearing race 56 upon which grid ring 18 is mounted.

The reduction gear train 81-84 is carried in a housing or gear box 98 which along with the turbine 76 is mounted upon the frame of motor 12 by screws 99 and 100. The connection at screw 99 forms a fixed pivot and the connection at screw 100, the latter passed through a slot 100a in the housing permits of a slight adjustment in order to effect a proper mesh between the last output gear 84 of the gear train and the combined gear and bearing race 56.

Reverting to valve 60, it will also be seen from Figs. 6 and 7 that pipe 55 which supplies water to impeller disk 13 connects with another internal passageway 85 in wall 63 leading to the upper valve chamber 61. As previously explained valve stem 64 is normally loaded by spring 71 in a downward direction as viewed in Fig. 6 so that lower chamber 62 normally communicates with passageways 72 and 74 and thus water entering valve 60 from inlet pipe 15 will pass out of the valve through line 75 leading to turbine 76. When however valve stem 64 is moved in an upward direction from that shown in Fig. 6 so as to close off lower chamber 62 from passageway 72 and place the latter in communication with upper chamber 61, water entering the valve will pass out of the same through pipe 55 and be delivered to the impeller disk 13 for atomizing.

Valve stem 64, in effect, terminates in a control button 86 which projects slightly beyond the face of the lower end closure plate of the valve casing and button 86 is arranged to lie in the path of a cam 87 formed at the outer, free end of an arm 88. The inner end of arm 88 is pivotally mounted at 89 upon one face of a multi-lobed circular cam plate 90 and a spring 91 associated with the arm serves to load it clockwise, as viewed in Fig. 3, against stop pin 92. A second stop pin 93 serves to limit motion of arm 88 in the opposite direction of movement.

Cam plate 90 is rotatably mounted at its center on a stud 94 which threads into the wall of valve 60 and the four lobes 95 of the cam which are located on the opposite side from the pivotally mounted cam 87 are adapted to be contacted in succession by the one or more circumferentially spaced rollers 96 mounted on grid ring 18. As viewed in Fig. 1, rotation of turbine rotor 79 counterclockwise effects rotation of grid ring 18 in a

clockwise direction. Hence as each roller 96 (two are used in the illustrated embodiment spaced 180° apart) comes into engagement with the cam lobes 95, cam plate 90 will be caused to advance counterclockwise through an angle of 90°. In the case of the illustrated construction, cam 87 is always located just to the left of valve control button 86 at the start of a humidifying operation and hence four successive engagements between the rollers 96 and cam lobes 95 requiring two revolutions of grid ring 18 will effect one complete revolution of cam plate 90 thus bringing cam 87 into engagement with valve control button 86. When contact between the leading edge of cam 87 and button 86 is established as plate 90 rotates, the loading effect on the button by spring 71 will result in cam 87 and arm 88 being rotated slightly clockwise about pivot 89 against the loading of spring 91 until it abuts stop pin 93. Continued rotation of plate 90 and cam 87 then causes button 86 to move upwardly. The arrangement of the valve parts is such that when button 86 and hence valve stem 64 also has moved for approximately 50% of its stroke, the pressure from the water acting against diaphragm 68 will cause the stem 64 to move quickly to the opposite position from that shown in Fig. 6 to thus cut off the water from turbine 76 and route it through pipe 55 to the impeller 13. Movement of button 86 to its extreme upward position will then permit cam 87 to resume its spring loaded position against the forward stop pin 92 and thus remove itself out of the path of button 86 so as not to interfere with downward movement of the button under the restoring force of spring 71 when water is cut off at valve 20 at the end of the humidifying operation.

For cleaning off the lip of the shroud or casing 10 which is located adjacent the periphery of grid ring 18, the latter can be provided with a brush or blade 97 which bears against and cleans the casing lip as ring 18 is rotated.

Operation

It is believed that the manner in which the cleaning device for the teeth of the grid ring operates will be clearly understood from the foregoing description. However, in brief resumé, when there is no call for moisture, control 21 occupies a position such that valve 20 is cut off and cam 87 is located just to the right of button 86 controlling valve 60. Motor 12 and the impeller disk 13 rotate continuously although this is not necessarily when valve 20 is closed.

Assuming there is now a call for additional moisture in the air stream, as soon as valve 20 is opened by control 50 21 water will flow under pressure through pipe 15 to valve 60, through this valve to pipe 75, and thence to turbine 76 causing the turbine rotor 79 to revolve. Rotary motion of rotor 79 is transmitted through the reduction gear train 80-8A to the ring gear or outer race 56 to 55 which grid ring 18 is attached thus effecting rotation of the latter, and the grid-teeth 19 will be cleaned as they move past the streams of water issuing from the two convergently arranged nozzle ports 59a in the nozzle head 59 which is connected in the pipe line 75.

As grid ring 18 rotates the two 180° displaced rollers 96 will engage the cam lobes 95 in succession and thus rotate cam plate 90. In the present embodiment cam plate 90 is advanced 90° for each engagement by each roller 96, and since there are two of the latter, it will

65 require two revolutions of grid ring 18 to effect one revolution of cam plate 90. After one revolution of plate 90, cam 87 will be brought against and cause upward movement of button 86 and valve stem 64, thus tripping the valve stem to its other position which cuts outlet pipe 76 and connects outlet pipe 55 to inlet pipe 15. This stops turbine rotor 79, thus bringing the reduction gear train and grid ring 18 to a standstill, and water is delivered instead through pipe 55 to the impeller disk 13 for atomizing and entraining with the passing air stream.

70 75 Rotation of the blade 97 with grid ring 18 also serves

to clean off the lip 10a of casing 10. Blade 97 bears against the lip 10a and the friction therebetween also serves as a brake to prevent the grid ring 18 from overrunning its predetermined angular travel of 720°.

Water will continue to be delivered to impeller disc 13 through pipe 55 until the desired condition of humidity, as determined by the setting of control 21, is reached whereupon valve 20 will close cutting off flow of all water to the humidifier. This then completes one cycle of operation and the device is ready to begin a new cycle as soon as further moisture is needed in the air stream passing by the unit.

In conclusion, I desire it to be made clear that the illustrated embodiment is to be considered typical rather than limitative of the structure which may be developed to carry out my inventive concept as defined in the appended claims. A brush type of cleaner could be substituted for the spray jets shown, and it is also of course possible to provide more or less than two revolutions of grid ring 18 by modifying the cam lobes 95 or changing the number of rollers 96 or cams 87. Using only one of the latter, instead of the pair illustrated, would for example require four revolutions of grid ring 18 to effect an actuation of valve 60. Other modifications along this line will also be suggested.

I claim:

1. A self-cleaning humidifier comprising a water inlet adapted to be connected to a source of water under pressure, a rotatable impeller to which water is delivered from said inlet, a motor connected to said impeller for rotating the same, a rotatable grid ring disposed adjacent said impeller for atomizing water distributed to it by said impeller, cleaning means cooperative with said grid ring for cleaning the teeth of said ring as the latter is rotated, a turbine coupled to said grid ring for effecting rotation thereof, and valve controlled pipe means extending to said turbine from said water inlet.

2. A self-cleaning humidifier as defined in claim 1 wherein the water discharged from said turbine is fed to said impeller.

3. A self-cleaning humidifier comprising a water inlet adapted to be connected to a source of water under pressure, a rotatable impeller to which water is delivered from said inlet, a motor connected to said impeller for rotating the same, a rotatable grid ring disposed adjacent said impeller for atomizing water distributed to it by said impeller, a nozzle positioned to direct a stream of water against the teeth of said grid ring for cleaning the teeth as said grid ring is rotated, a turbine coupled to said grid ring for effecting rotation thereof, and valve controlled pipe means extending to said turbine and nozzle from said water inlet.

4. A self-cleaning humidifier comprising a water inlet adapted to be connected to a source of water under pressure, a rotatable impeller for distributing water delivered thereto, a motor connected to said impeller for rotating the same, first pipe means for conveying water from said inlet to said impeller, a rotatable grid ring disposed adjacent said impeller for atomizing water distributed to it by said impeller, a cleaning device adapted to clean the teeth of said grid ring as the latter is rotated, a turbine coupled to said grid ring for effecting rotation thereof, second pipe means for conveying water from said inlet to said turbine, and valve means controlling flow of water through said first and second pipe means.

5. A self-cleaning humidifier comprising an impeller for distributing water delivered thereto under pressure, a rotatable grid ring disposed adjacent said impeller for atomizing water distributed by said impeller, a cleaning device cooperative with said grid ring, and means effecting rotation of said grid ring comprising a turbine, a pipe for conveying water under pressure to said turbine and valve means in said pipe controlled by said grid ring for terminating water flow to said turbine upon completion of a predetermined rotary travel of said grid ring.

6. A self-cleaning humidifier comprising a water inlet, an impeller for distributing water delivered thereto under pressure from said inlet, a motor connected to said impeller for rotating the same, a rotatable grid ring disposed adjacent said impeller for atomizing water distributed by said impeller, a cleaning device cooperative with said grid ring, a turbine for effecting rotation of said grid ring, and means effecting delivery of water to said turbine at the beginning of each humidifying period.

7. A self-cleaning humidifier comprising a casing, a water inlet to said casing, a motor driven impeller within said casing for distributing water delivered thereto under pressure from said inlet, a rotatable assembly mounted within said casing said assembly comprising a toothed grid ring located adjacent said impeller and a ring gear, a cleaning device adapted to cooperate with said grid ring for cleaning the grid teeth, a turbine, a gear train coupling the turbine rotor to said ring gear, a pipe extending from said inlet to the rotor of said turbine for effecting rotation thereof and of said rotatable assembly, a second pipe extending from said inlet to said impeller and valve means disposed in said pipes for selectively controlling flow of water between said inlet and said first and second pipes.

8. A self-cleaning humidifier as defined in claim 7 wherein said valve means is controlled by said rotatable assembly.

9. A self-cleaning humidifier comprising a water inlet adapted to be connected to a source of water under pressure, a rotatable impeller for distributing water delivered thereto, a rotatable grid ring disposed adjacent said impeller for atomizing water distributed to it by said impeller, a cleaning device adapted to clean the teeth of said grid ring as the latter is rotated, a turbine coupled to said grid ring for effecting rotation thereof, a control valve, actuating means for said valve, said valve having an inlet communicable alternatively with one or the other of a pair of outlets, pipes leading from said outlets to said impeller and turbine, respectively, another pipe leading from said water inlet to the inlet on said valve, a rotatable cam plate, means carried by said cam plate and movable into engagement with said valve actuating means, and cam actuating means carried by said grid ring and engageable with said cam plate for rotating the latter through a predetermined angle for each predetermined angular movement of said grid ring.

10. A self-cleaning humidifier as defined in claim 9 wherein said valve is normally spring loaded to a position connecting the valve inlet with that outlet leading to said turbine.

11. A self-cleaning humidifier as defined in claim 9 wherein said cam plate includes a plurality of cam surfaces engaged in succession by said cam actuating means.

12. A self-cleaning humidifier comprising a water inlet adapted to be connected to a source of water under pressure, a rotatable impeller to which water is delivered from said inlet, a motor connected to said impeller for rotating the same, a rotatable grid ring disposed adjacent said impeller for atomizing water distributed to it by said impeller, cleaning means cooperative with said grid ring for cleaning the teeth of said ring as the latter is rotated, a turbine coupled to said grid ring for effecting rotation thereof, said turbine being driven by water under pressure supplied thereto from said inlet.

13. A self-cleaning humidifier comprising a water inlet adapted to be connected to a source of water under pressure, a rotatable impeller for distributing water delivered thereto, a rotatable grid ring disposed adjacent said impeller for atomizing water distributed to it by said impeller, a cleaning device adapted to clean the teeth of said grid ring as the latter is rotated, a turbine coupled to said grid ring for effecting rotation thereof, a control valve, said valve including a pair of valve chambers, a first outlet leading to said impeller from one of said chambers, a second outlet leading to said turbine from the other of said chambers, an inlet adapted to establish

communication between said water inlet and valve chambers and a valve stem controlling flow of water selectively between said valve inlet and valve chambers, and means controlled by rotation of said grid ring for actuating said valve stem.

14. A self-cleaning humidifier as defined in claim 13 wherein one wall of each of said valve chambers is constituted by a diaphragm connected to said valve stem, and which further includes spring means normally biasing said valve stem to a position wherein said valve inlet

10

communicates with the valve chamber through which water flows to said second outlet.
